(57) **ABSTRACT**

A flip-top closure includes a spout, a lid, and a hinge member. The spout is configured for coupling with a fitment of a container. The spout includes a base portion, a tip portion, and a main body. The base portion defines a retention receptacle and an inlet. The inlet includes a first diameter. The tip portion extends from the base portion and defines a dispensing outlet. The base portion and the tip portion cooperate to define a passageway that extends between the inlet and the dispensing outlet. The lid includes a main body that includes an upper wall and a sidewall that cooperate to define an interior. The hinge member is coupled with each of the spout and the sidewall of the main body. The hinge member is configured to facilitate pivoting of the lid between a closed position and an opened position.

FIG. 4

FIG. 7

FIG. 8

FIG. 9

FIG. 10

FLIP-TOP CLOSURE FOR CONTAINER

TECHNICAL FIELD

The systems and apparatuses described herein generally relate to a flip-top closure for a container. The flip-top closure includes a spout and a lid pivotally coupled with the spout.

BACKGROUND

Spouted pouches typically include a flexible pouch that contains a flowable product, such as a food product. When the flexible pouch is squeezed, the product contained in the flexible pouch can be dispensed through a fitment. A cap is releasably coupled with the fitment to prevent the flowable product from being inadvertently dispensed from the flexible pouch.

BRIEF DESCRIPTION OF THE DRAWINGS

It is believed that certain embodiments will be better understood from the following description taken in conjunction with the accompanying drawings in which:

FIG. 1 is an exploded isometric view depicting a flip-top closure in association with a container, with a lid shown in a closed position, in accordance with one embodiment;

FIG. 2 is an upper isometric view depicting the flip-top closure of FIG. 1, but with the lid shown in an opened position;

FIG. 3 is a lower isometric view depicting the flip-top closure of FIG. 1, with the lid shown in the closed position;

FIG. 4 is a cross-sectional view taken along the line 4-4 in FIG. 1;

FIG. 5 is an enlarged top plan view depicting a spout of the flip-top closure of FIG. 1;

FIG. 6 is an enlarged front isometric view depicting the lid of the flip-top closure of FIG. 1;

FIG. 7 is a front isometric view depicting the lid of the flip-top closure of FIG. 1, but in a partially opened position with a tamper evident feature inserted into the spout and separated from the lid;

FIG. 8 is an isometric view depicting a flip-top closure and a fitment, with a lid of the flip-top closure shown in an opened position, in accordance with another embodiment;

FIG. 9 is an exploded isometric view depicting the flip-top closure of FIG. 8, with the lid shown in the opened position and the fitment removed for clarity of illustration; and

FIG. 10 is a cross-sectional view taken along the line 10-10 in FIG. 8.

DETAILED DESCRIPTION

Selected embodiments are hereinafter described in detail in connection with the views and examples of FIGS. 1-10. As illustrated in FIG. 1, a flip-top closure 12 (hereinafter the “closure”) can be provided on a fitment 14 of a container 16. In one embodiment, the container 16 can be a squeezable pouch that contains a flowable product, such as liquid food (e.g., baby food). When the container 16 is squeezed, the flowable product can be dispensed through the fitment 14 and out of the closure 12 for consumption by a user. It is to be appreciated that although the container 16 is shown to be a squeezable pouch, the closure 12 can be used on any of a variety of suitable alternative flexible container arrangements, such as, for example, toothpaste tubes, food or drink

bottles (e.g., disposable or reusable bottles for dispensing a food or drink product) or hand cleaner dispenser bottles.

As illustrated in FIG. 2, the closure 12 can include a spout 18 and a lid 20. The spout 18 can include a base portion 22 and a tip portion 24 that extends from the base portion 22. The tip portion 24 can include an upper tip wall 25 that defines a dispensation outlet 26 from which flowable product can be dispensed to a user's mouth when the container 16 is squeezed. The upper tip wall 25 can include an upper surface 27. In one embodiment, the tip portion 24 can be substantially bell-shaped (e.g., with a smaller diameter proximate the dispensation outlet 26 and a larger diameter proximate the base portion 22) and thus contoured to a user's mouth to allow for easy consumption of flowable product dispensed from the dispensation outlet 26. It is to be appreciated that any of a variety of suitable alternative shapes are contemplated for the tip portion 24 to accommodate effective dispensation to a user. The base portion 22 can include a collar 28 that is substantially annularly shaped. In one embodiment, as illustrated in FIG. 2, the collar 28 can have a knurled profile that allows for effective gripping of the collar 28 (e.g., by an automated capping machine) to facilitate attachment of the closure 12 to the fitment 14 of the container 16.

As illustrated in FIGS. 1 and 2, the lid 20 can include a main body 30 that comprises an upper lid wall 32 and a sidewall 34 that cooperates with the upper lid wall 32 to define an interior 36 (FIG. 2). A sealing member 38 (FIG. 2) can be disposed in the interior 36 and can extend away from the upper lid wall 32. A stop member 39 can be disposed adjacent to the sealing member 38 (e.g., concentric with the sealing member 38) and can extend away from the upper lid wall 32. A hinge member 40 can be coupled with each of the spout 18 and the sidewall 34. The hinge member 40 can be configured to facilitate pivoting of the lid 20 with respect to the spout 18 between a closed position (FIG. 1) and an opened position (FIG. 2). In one embodiment, the hinge member 40 can be a living hinge. As illustrated in FIG. 2, the collar 28 can define a notch 42 that is configured to accommodate the hinge member 40. When the lid 20 is in the closed position, as illustrated in FIG. 1, the hinge member 40 can be disposed in the notch 42 such that the hinge member 40 substantially corresponds with the overall profile of the collar 28. In one embodiment, as illustrated in FIG. 1, the sidewall 34 can define a finger notch 44 that accommodates a user's finger for manually pivoting the lid 20 between the opened and closed positions.

The spout 18, the lid 20, and the hinge member 40 can be formed together as a unitary one-piece construction. In one embodiment, the spout 18, the lid 20, and the hinge member 40 can be formed of a thermoplastic or elastomeric material via compression molding, injection molding, thermoforming, blow molding, three-dimensional printing, or any of a variety of other suitable alternative formation processes. In other embodiments, the spout 18, the lid 20, and the hinge member 40 can be formed of material other than thermoplastic or elastomeric material, such as paperboard, glass, rubber, elastomers, thermoset plastics, and/or metal, for example. In some embodiments, the spout 18, the lid 20, and the hinge member 40 might not be formed as a unitary one-piece construction but instead can be an assembly of discrete components.

Referring now to FIGS. 3 and 4, the base portion 22 of the spout 18 can define an inlet 46 that comprises a diameter D1. The base portion 22 and the tip portion 24 can cooperate to define a passageway 48 that extends between the inlet 46 and the dispensation outlet 26. When the closure 12 is coupled

with the container 16, the fitment 14 can extend at least partially into the inlet 46 such that flowable product dispensed from the fitment 14 can flow through the fitment 14 and out of the dispensation outlet 26 when the lid 20 is in the opened position. When the lid 20 is in the closed position, as illustrated in FIG. 4, the upper lid wall 32 can overlie the dispensation outlet 26 and the sealing member 38 can extend into the dispensation outlet 26. The sealing member 38 can interface with the upper tip wall 25 in an interference fit which can create an effective seal therebetween while also selectively retaining the lid 20 in the closed position. The stop member 39 can contact the upper surface 27 of the upper tip wall 25 to serve as a functional stop which can ensure consistent sealing between the sealing member 38 and the upper tip wall 25 each time the lid 20 is in the closed position. The lid 20 can be pivoted from the closed position to the opened position by urging the lid 20 away from the closed position with enough force to overcome the interference fit between the upper tip wall 25 and the sealing member 38. In one embodiment, the sealing member 38 can be formed together with the lid 20 in a unitary one-piece construction. In another embodiment, the sealing member 38 can be formed separately from the lid 20 and attached with adhesive or other coupling arrangement.

In one embodiment, as illustrated in FIGS. 3 and 4, the base portion 22 can comprise a threaded collar 50 that defines the inlet 46 and is configured for threaded engagement with the fitment 14. The closure 12 can be threaded onto or off of the fitment 14 by rotating the closure 12 in a tightening or loosening direction (e.g., clockwise and counter-clockwise). It is to be appreciated that the base portion 22 can include any of a variety of suitable alternative coupling arrangements for releasably securing a fitment of a container relative to an inlet, such as a bayonet connection, for example.

As illustrated in FIG. 3, a plurality of rib members 52 can extend between the collar 28 and the threaded collar 50 to distribute some of the rotational force from the collar 28 to the threaded collar 50 when the collar 28 is grasped and rotated (e.g., to remove or install the closure 12 on the fitment 14 of the container 16). A pair of locking members 54 can extend from the threaded collar 50 and can interact with corresponding stop members 56 (FIG. 1) to facilitate alignment of the closure 12 on the container 16 as well as to serve as a tamper evident feature that indicates whether the closure 12 has been removed from the container 16 after installation. For example, when the closure 12 is tightened onto the fitment 14 of the container 16, each locking member 54 can eventually interact with one of the stop members 56. As the closure 12 is further tightened, respective angled surfaces 53 of the locking members 54 can travel over the corresponding stop members 56 until the locking members 54 clear the respective stop members 56 thereby indicating that the closure 12 is sufficiently tightened and is properly aligned on the container 16 (e.g., in a position that is convenient for a user to open the lid 20 and consume flowable material from the closure 12). If the closure 12 is subsequently loosened (e.g., by rotating the closure 12 in a counter-clockwise direction), respective vertical surfaces 55 of the locking members 54 can interface with the stop members 56 to restrict loosening of the closure 12. If the closure 12 is further loosened, the locking members 54 can break against the stop members 56 to provide a visual indication that the closure 12 has been removed from the container 16 (e.g., tampered with). It is to be appreciated that, during a filling and capping process, each time a closure (e.g., 12) is installed on a container (e.g., 16), the locking

members 54 and the stop members 56 can cooperate to facilitate consistent and repeatable positioning of each closure on a given container (e.g., 16). It is also to be appreciated that, although two locking members 54 and two stop members 56 are illustrated, any quantity (e.g., one or more than two) of locking members 54 and stop members 56 are contemplated.

Still referring to FIGS. 3 and 4, the tip portion 24 can comprise an annular shoulder 58 that is disposed in the passageway 48 adjacent the dispensation outlet 26. The annular shoulder 58 can extend from the upper tip wall 25 towards the inlet 46 and can comprise a diameter D2 that is less than the diameter D1 of the inlet 46. An internal rib member 60 can extend radially inwardly from the annular shoulder 58.

Referring now to FIGS. 3-5, the base portion 22 of the spout 18 can define a retention receptacle 62 on an opposite side of the spout 18 from the hinge member 40. As illustrated in FIGS. 3 and 4, the base portion 22 of the spout 18 can include an interior sidewall 64 that extends along a portion of the collar 28 and cooperates with the collar 28 to define the retention receptacle 62. As illustrated in FIGS. 4 and 5, the interior sidewall 64 can include a floor portion 66 that extends towards the collar 28 and is spaced from the collar by a distance L1 (FIG. 4). As illustrated in FIG. 4, the base portion 22 can include a flange member 68 that is disposed in the retention receptacle 62 and extends from the collar 28 towards the interior sidewall 64. The flange member 68 can be spaced from the interior sidewall 64 by a distance L2.

Referring now to FIGS. 2, 4, and 6, the lid 20 can comprise a tamper evident feature 70 and a plurality of frangible members 72 (FIG. 6). The tamper evident feature 70 can extend away from the sidewall 34. The plurality of frangible members 72 can be coupled to each of the sidewall 34 and the tamper evident feature 70. As will be described in further detail below, the plurality of frangible members 72 can serve as a frangible connection between the sidewall 34 and the tamper evident feature 70 such that the tamper evident feature 70 can be torn away from the sidewall 34 when the lid 20 is opened. In one embodiment, as illustrated in FIG. 6, each of the frangible members 72 can have a substantially trapezoidal cross-sectional shape that have an upper frangible connection. It is to be appreciated that one or more frangible members can be provided in any of a variety of shapes, sizes, and/or configurations.

The tamper evident feature 70 can include a finger member 74. When the lid 20 is in the closed position, as illustrated in FIG. 4, the tamper evident feature 70 can extend into the retention receptacle 62 such that the finger member 74 is disposed beneath the flange member 68 of the base portion 22. The finger member 74 and the flange member 68 can interact with each other to prevent the tamper evident feature 70 from being pulled out of the retention receptacle 62. As such, when the frangible members 72 are intact, the finger member 74 and the flange member 68 can cooperate to maintain the lid 20 in the closed position. However, when the lid 20 is pivoted from the closed position into the opened position, the finger member 74 and the flange member 68 can cooperate to irreversibly decouple the tamper evident feature 70 from the lid 20 at the frangible members 72 to provide a visual indication, and in some cases an audible indication, that the lid 20 has been opened, as illustrated in FIG. 7. A user of the closure 12 can accordingly rely on the tamper evident feature 70 to determine whether the closure 12 may have been tampered with or previously opened.

In one embodiment, when the lid 20 is in the closed position, as illustrated in FIG. 4, the finger member 74 and the flange member 68 can be spaced vertically from each other. As such, when the lid 20 is moved from the opened position, to begin opening the lid 20, the finger member 74 can move upwardly slightly before engaging the flange member 68 which can allow the lid 20 to gain momentum to encourage tearing of the tamper evident feature 70 from the lid 20.

Once the tamper evident feature 70 has been separated from the lid 20, the collar 28 and the interior sidewall 64 can cooperate to retain the tamper evident feature 70 in the retention receptacle 62 which can reduce the risk of the tamper evident feature becoming dislodged from the lid 20 and possibly becoming a choking hazard. The finger member 74 can have a thickness L3 that is greater than the distances L1 and L2. Even though the finger member 74 is thicker than the distance L2 between the flange member 68 and the interior sidewall 64, the overall shape of the finger member 74 and/or the compliance of the material used for the closure 12 can allow the tamper evident feature 70 to be inserted into the retention receptacle 62 (e.g., during assembly of the closure 12). However, once the tamper evident feature 70 is inserted into the retention receptacle 62 and then separated from the lid 20, the relative thickness L3 of the finger member 74 as compared with the distances L1 and L2 can effectively trap the tamper evident feature 70 within the retention receptacle 62.

An alternative embodiment of a closure 112 is illustrated in FIGS. 8-10 and is similar to, or the same in many respects as, the closure 12 illustrated in FIGS. 1-7. For example, the closure 112 can include a spout 118, a lid 120, and a hinge member 140 coupled with each of the spout 118 and the lid 120. The spout 118 can include a base portion 122 and a tip portion 124. The tip portion 124 can include an upper tip wall 125 that defines a dispensation outlet 126. As illustrated in FIG. 10, the base portion 122 can comprise a threaded collar 150 that defines an inlet 146. A passageway 148 can extend between the dispensation outlet 126 and the inlet 146. An annular shoulder 158 can be disposed in the passageway 148 and can extend from the upper tip wall 125 towards the inlet 146. An internal rib member 160 can extend radially inwardly from the annular shoulder 158. A fitment 114 of a container (not shown) can be threadably coupled with the threaded collar 150 and can extend into the passageway 148. The fitment 114 can extend into an annular groove 178 defined between the annular shoulder 158 and a sidewall 135 of the tip portion 124. The fitment 114 can engage the tip portion 124 in the annular groove 178 to create a sealing interface therebetween.

However, as illustrated in FIGS. 9 and 10, a retaining member 180 and a flexible membrane 182 can be associated with the closure 112. The retaining member 180 can comprise an outer collar 184 and an inner collar 186 disposed radially inwardly of the outer collar 184. The outer collar 184 can have a larger diameter than the inner collar 186. The outer collar 184 and the inner collar 186 can be coupled together with a plurality of rib members 188 (two shown) that extend therebetween. The outer and inner collars 184, 186 can be vertically offset from each other such that the outer collar 184 is elevated with respect to the inner collar 186 (see FIG. 10). An external rib member 190 can extend radially outwardly from the outer collar 184.

The retaining member 180 can be formed together as a unitary one-piece construction. In one embodiment, the retaining member 180 can be formed of a thermoplastic via extrusion, injection molding, thermoforming, blow molding,

three-dimensional printing, or any of a variety of other suitable alternative thermoplastic formation processes. In some embodiments, the retaining member 180 might instead be formed of an assembly of discrete components.

Still referring to FIGS. 9 and 10, the flexible membrane 182 can comprise a dispensation body 192 and a gasket 194 coupled with and surrounding the dispensation body 192. The dispensation body 192 can define a slotted port 196. In one embodiment, the flexible membrane 182 can be formed of an elastomeric material, such as rubber or silicone, but in other embodiments can be formed of any of a variety of suitable alternative flexible materials.

Referring now to FIG. 10, the flexible membrane 182 can be disposed in the passageway 148 adjacent to the upper tip wall 125. The dispensation body 192 can be located beneath the dispensation outlet 126 such that the dispensation outlet 126 and the slotted port 196 are in fluid communication with each other. The retaining member 180 can be disposed in the passageway 148 adjacent to the flexible membrane 182 such that at least a portion of the flexible membrane 182 is sandwiched between upper tip wall 125 and the retaining member 180. In one embodiment, as illustrated in FIG. 10, the gasket 194 can be sandwiched between the inner collar 186 and a collar portion 198 of the upper tip wall 125.

The retaining member 180 can be coupled with the annular shoulder 158 to facilitate retention of the flexible membrane 182 within the tip portion 124. In one embodiment, as illustrated in FIG. 10, the retaining member 180 can fit onto the annular shoulder 158 such that the internal rib member 160 of the annular shoulder 158 and the external rib member 190 of the outer collar 184 interface with each other to couple the retaining member 180 to the annular shoulder 158. In such an embodiment, the internal rib member 160 and the external rib member 190 can cooperate to urge the inner collar 186 and the collar portion 198 together enough to compress the gasket 194 thereby creating an effective seal therebetween. During assembly of the closure 112, the flexible membrane 182 can be installed in the tip portion 124 by simply pressing the retaining member 180 onto the annular shoulder 158 over the flexible membrane 182, which can be more cost effective and efficient than conventional flip-top closures that incorporate a membrane.

When flowable product is not being dispensed from the closure 112, the flexible membrane 182 can be provided in a concave shape, as illustrated in FIGS. 8 and 10. When the container (e.g., 16) is squeezed to dispense flowable product from the closure 112, the flexible membrane 182 can flex upwardly and into a convex shape to allow the flowable product to be dispensed through the slotted port 196. When the container is released to stop dispensing flowable product, the flexible membrane 182 can be returned to the concave shape and the flowable product can be slightly withdrawn back into the fitment 114. It is to be appreciated that the retaining member 180 can be any of a variety of suitable alternative arrangements that facilitates coupling of the flexible membrane 182 to the tip portion 124. It is also to be appreciated that the flexible membrane 182 can be any of a variety of suitable alternative arrangements for controlling dispensation of flowable product from the dispensation outlet 126.

It is to be appreciated that, in one embodiment, the closures 12, 112 illustrated in FIGS. 1-7 and 8-10, respectively, can be cross-compatible such that any closure can be converted into the arrangement shown in FIGS. 1-7 or the assembly shown in FIGS. 8-10 by simply omitting or adding, respectively, the retaining member 180 and the flexible membrane 182. This cross-compatible configuration

can provide a more cost effective and efficient solution for implementing or omitting a membrane on a closure than conventional closure configurations which utilize different closure designs depending upon whether a membrane is being implemented or not.

The foregoing description of embodiments and examples of the disclosure has been presented for purposes of illustration and description. It is not intended to be exhaustive or to limit the disclosure to the forms described. Numerous modifications are possible in light of the above teachings. Some of those modifications have been discussed and others will be understood by those skilled in the art. The embodiments were chosen and described in order to best illustrate the principles of the disclosure and various embodiments as are suited to the particular use contemplated. The scope of the disclosure is, of course, not limited to the examples or embodiments set forth herein, but can be employed in any number of applications and equivalent devices by those of ordinary skill in the art. Rather it is hereby intended the scope of the invention be defined by the claims appended hereto. Also, for any methods claimed and/or described, regardless of whether the method is described in conjunction with a flow diagram, it should be understood that unless otherwise specified or required by context, any explicit or implicit ordering of steps performed in the execution of a method does not imply that those steps must be performed in the order presented and may be performed in a different order or in parallel.

What is claimed is:

1. A flip-top closure for a container, the flip-top closure comprising:

a spout configured for coupling with a fitment of a container, the spout comprising:

a base portion defining a retention receptacle and an inlet, wherein the inlet comprises a first diameter; and

a tip portion extending from the base portion and defining a dispensation outlet, wherein the base portion and the tip portion cooperate to define a passageway that extends between the inlet and the dispensation outlet;

a lid comprising:

a main body comprising an upper lid wall and a sidewall that cooperate to define an interior; and

a tamper evident feature extending away from the sidewall; and

at least one frangible member coupled with each of the sidewall and the tamper evident feature; and

a hinge member coupled with each of the spout and the sidewall of the main body, the hinge member configured to facilitate pivoting of the lid between a closed position and an opened position, wherein:

when the lid is in the closed position, the upper lid wall overlies the dispensation outlet to provide a fluid seal therebetween, and the tamper evident feature extends into the retention receptacle;

when the lid is pivoted from the closed position to the opened position, the tamper evident feature is decoupled from the lid at the at least one frangible member and is retained within the retention receptacle;

the tamper evident feature comprises a finger member; the base portion comprises a flange member disposed in the retention receptacle;

when the lid is moved from the closed position to the opened position, the finger member and the flange

member cooperate to facilitate decoupling of the tamper evident feature at the at least one frangible member from the lid;

the base portion comprises a collar and an interior wall that extends along a portion of the collar and cooperates with the collar to define the retention receptacle;

the interior wall comprises a floor portion that extends towards the collar and is configured to facilitate retention of the flange member within the retention receptacle; and

the floor portion is spaced from the collar by a first distance and the finger member has a thickness that is greater than the first distance.

2. The flip-top closure of claim 1 wherein the flange member extends from the collar and is spaced from the interior wall by a second distance, and the thickness of the finger member is greater than the second distance.

3. The flip-top closure of claim 1 wherein the base portion comprises a threaded collar that defines the inlet and is configured for threaded engagement with a fitment of a container.

4. The flip-top closure of claim 1 wherein the tip portion further comprises an upper tip wall that defines the dispensation outlet.

5. The flip-top closure of claim 4 wherein the tip portion further comprises an annular shoulder that extends from the upper tip wall towards the inlet and comprises a second diameter that is shorter than the first diameter.

6. The flip-top closure of claim 5 wherein the tip portion further comprises an internal rib member that extends radially inwardly from the annular shoulder.

7. The flip-top closure of claim 1 wherein the lid further comprises a sealing member that is disposed in the interior and extends away from the upper lid wall, wherein the sealing member extends at least partially into the dispensation outlet when the lid is in the closed position.

8. The flip-top closure of claim 1 further comprising: a flexible membrane disposed in the passageway adjacent the dispensation outlet; and

a retaining member, wherein:

the tip portion comprises an upper tip wall that defines a dispensation outlet and an annular shoulder that extends from the upper tip wall towards the inlet; and

the retaining member is disposed in the passageway adjacent the flexible membrane such that at least a portion of the flexible membrane is sandwiched between the retaining member and the upper tip wall.

9. The flip-top closure of claim 8 wherein the retaining member comprises an outer collar and an inner collar coupled with the outer collar and disposed radially inwardly of the outer collar.

10. The flip-top closure of claim 9 wherein:

the tip portion comprises an internal rib member that extends radially inwardly from the annular shoulder; and

the retaining member comprises an external rib member that extends radially outwardly from the outer collar and interfaces with the internal rib member to facilitate coupling of the retaining member with the annular shoulder.

11. The flip-top closure of claim 10 wherein the flexible membrane comprises a dispensation body and a gasket coupled with and surrounding the dispensation body.

12. The flip-top closure of claim 11 wherein the gasket is disposed between each of the inner collar, the outer collar, and the upper tip wall to facilitate an effective seal therebetween.

13. An assembly comprising:

- a flip-top closure for a container, the flip-top closure comprising:
  - a spout configured for coupling with a fitment of a container, the spout comprising:
  - a base portion defining a retention receptacle and an inlet, wherein the inlet comprises a first diameter;
  - and
  - a tip portion extending from the base portion and comprising:
  - an upper tip wall that defines a dispensation outlet, wherein the base portion and the tip portion cooperate to define a passageway that extends between the inlet and the dispensation outlet;
  - and
  - an annular shoulder that extends from the upper tip wall towards the inlet and comprises a second diameter that is shorter than the first diameter;
  - a lid comprising:
  - a main body comprising an upper lid wall and a sidewall that cooperate to define an interior; and
  - a tamper evident feature extending away from the sidewall; and
  - at least one frangible member coupled with each of the sidewall and the tamper evident feature; and
  - a hinge member coupled with each of the spout and the sidewall of the main body, the hinge member configured to facilitate pivoting of the lid between a closed position and an opened position;
  - a flexible membrane disposed in the passageway adjacent the dispensation outlet; and
  - a retaining member disposed in the passageway adjacent the flexible membrane such that at least a portion of the flexible membrane is sandwiched between the retaining member and the upper tip wall, wherein:
- when the lid is in the closed position, the upper lid wall overlies the dispensation outlet to provide a fluid seal therebetween, and the tamper evident feature extends into the retention receptacle;
- when the lid is pivoted from the closed position to the opened position, the tamper evident feature is

decoupled from the lid at the at least one frangible member and is retained within the retention receptacle;

the tamper evident feature comprises a finger member; the base portion comprises:

a flange member disposed in the retention receptacle; a collar; and

an interior wall that extends along a portion of the collar and cooperates with the collar to define the retention receptacle, the interior wall comprising a floor portion that extends towards the collar and is configured to facilitate retention of the flange member within the retention receptacle;

when the lid is moved from the closed position to the opened position, the finger member and the flange member cooperate to facilitate decoupling of the tamper evident feature at the at least one frangible member from the lid;

the floor portion is spaced from the collar by a first distance and the finger member has a thickness that is greater than the first distance; and

the flange member extends from the collar and is spaced from the interior wall by a second distance, and the thickness of the finger member is greater than the second distance.

14. The assembly of claim 13 wherein:

- the retaining member comprises an outer collar and an inner collar coupled with the outer collar and disposed radially inwardly of the outer collar;
- the tip portion comprises an internal rib member that extends radially inwardly from the annular shoulder; the retaining member comprises an external rib member that extends radially outwardly from the outer collar and interfaces with the internal rib member to facilitate coupling of the retaining member with the annular shoulder;
- the flexible membrane comprises a dispensation body and a gasket coupled with and surrounding the dispensation body; and
- the gasket is disposed between each of the inner collar, the outer collar, and the upper tip wall to facilitate an effective seal therebetween.

15. A kit comprising a container and the assembly of claim 13.
